(57) **CLAIM**

The ornamental design for an electronic device case, as shown and described.

DESCRIPTION

FIG. 1 is a front perspective view of the electronic device case;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a bottom plan view thereof; and,

FIG. 8 is a top plan view thereof.

The broken lines throughout the drawing figures depict stitching which is part of the claimed design.
